UNITED STATES PATENT OFFICE

CLARENCE A. ANDERSON, OF CHICAGO, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

INTERCOMMUNICATING SYSTEM

Application filed February 18, 1929. Serial No. 340,740.

This invention relates in general to telephone systems, but is more particularly concerned with small intercommunicating or private branch systems, especially of the 5 trunk connected type; and the object of the invention, briefly stated, is the provision of new and improved circuit arrangements which are particularly suitable for use in such small telephone systems.

10 A particular feature of the invention relates to the improved circuit arrangements and apparatus whereby each subscriber is enabled to act in the capacity of an attendant operator; that is, each subscriber can answer 15 any incoming trunk call, and can then signal and transfer the call to any other local subscriber.

Another feature of the invention relates to 20 the circuit arrangements which prevent other local subscribers from interfering or coming in on the trunk after a local subscriber has seized an idle trunk or answered an incoming call on an inter-office trunk.

Another feature of the invention relates 25 to the manner in which the local subscribers are visually signalled so that they know at all times which trunks are busy, which trunks are idle, and which trunk they should come in on in order to answer the call.

30 The foregoing and other features not specifically mentioned may be described more in detail by referring to the drawings comprising Figs. 1 and 2, which, when Fig. 2 is placed to the right of Fig. 1, show by means of the 35 usual circuit diagrams a sufficient amount of apparatus to enable the invention to be described and understood.

In Fig. 1 is shown the equipment individual to local subscriber's lines. A and A', one 40 inter-communicating trunk comprising conductors 3 to 6, inclusive, two inter-office trunks comprising conductors 7 to 10, inclusive, and 11 to 14, inclusive, of which only 45 the talking conductors 7, 8, 11, and 12 extend to the main exchange, and a number of common conductors comprising conductors 15 to 18, inclusive.

50 In the upper left hand corner of Fig. 2 is shown the equipment, comprising mostly re-

lays, which is associated with the above-mentioned trunks at the local exchange.

In the right and lower halves of Fig. 2 is shown the equipment at the main exchange which is associated with the above-mentioned inter-office trunks. The trunk conductors 11 and 12 terminate in the rotary line switch RS and in the banks of connectors such as the connector C. The trunk conductors 7 and 8 terminate in a rotary line switch RS' and in the banks of connectors such as connector C. The rotary line switches have access to selector switches, such as S and S'. The rotary line switches may be of the well known type in which the wipers move in a 60 forward direction only and remain in the position last used. The selectors and connectors, such as S and C, may be of the well known Strowger type of switch having vertical and rotary motion.

Referring more in detail to Fig. 1, each local subscriber's individual equipment comprises a plurality of lamps, one for each trunk, a trunk key, such as TK, a combined ring and transfer key, such as CK, a line or connecting relay, a buzzer, and the substation equipment which is preferably of the so-called monophone cradle type comprising a calling device, a transmitter, an induction coil, and a receiver. The trunk keys are of the locking type and when moved to the left or right remain in such position until released by the subscriber, while the combined ring and transfer keys are of the non-locking type and must be held in operated position. The base of the monophone cradle set is preferably similar to the cradle set disclosed in Design Patent 68,929, issued December 1, 1925, to H. F. Obergfell. The lamps 23, 24, and 25 are mounted in a vertical row 90 in the front side of the monophone base at the left. The trunk key TK is mounted to the right and opposite the middle lamp, the normal position of the trunk key TK corresponding to the middle lamp and the up-and-down positions of the trunk key TK corresponding to the upper and lower lamps, respectively. The ring and transfer key is mounted to the right of the trunk key.

Having described the system and the appa- 100

ratus to be used, a detailed description of the operation thereof will now be given. For this purpose it will be assumed that the local subscriber at substation A wishes to converse with the local subscriber at substation A'.
 5 To establish the connection, the subscriber at substation A observes whether or not the lamp, in this case lamp 24, corresponding to the intercommunicating trunk, is lighted or not. In case the lamp 24 is lighted, subscriber A will know that the intercommunicating trunk is busy and will therefore wait until the lamp becomes dark, which is an indication that such trunk is idle. In case the
 10 lamp 24 is dark the subscriber A removes his monophone from the cradle set and thus closes a circuit for operating his line relay 42 as follows: from ground by way of common conductor 17, conductor 28, monophone cradle springs 44, winding of relay 42, resistance 41, normally closed springs controlled by spring 47, spring 51 and its resting contact, spring 34 and its resting contact, spring 30 and its resting contact, common conductor 5, and through the winding of relay 100 to battery. Relay 42, upon energizing, at armature 40 short circuits the resistance 41 so as to prevent any other local subscriber from seizing the intercommunicating trunk at this time; and at armatures 45 and 46 connects the substation circuit to the talking conductors 3 and 4 by way of the normally closed trunk key springs 35 and 36 and 31 and 32. Relay 100 also energizes
 15 over the above-traced circuit and at armature 101 completes a circuit for the intercommunicating lamp 24 as follows: from ground by way of armature 101, common conductor 6, conductor 21, lamp 24, and to battery over common conductor 16. A branch circuit may also be traced from grounded armature 101 through all of the lamps, such as 24', at each of the subscriber's stations and back to battery at common conductor 16. The
 20 operation of these lamps informs the subscribers that the intercommunicating trunk is busy.

It will be noted, that by the closure of armature 40 relay 42 shunted out the resistance 41 and the effect of this is to prevent any other local subscriber who may wish to make a call from coming in on the same trunk. For instance, in case subscriber A' should attempt connection with the intercommunicating trunk at this time, relay 42' would attempt to energize in series with resistance 41' and relay 100, similar to the way relay 42 was energized. In other words, relay 42' and resistance 41' are connected in parallel with relay 42. Under these conditions relay 42' cannot pull up because of the shunting effect of relay 42, which is of lower resistance than the resistance 41 or 41'. It follows, therefore, that since relay 42' does
 25 not receive sufficient current to fully ener-

gize, any subscriber such as subscriber A' is prevented from coming in on the intercommunicating trunk to initiate a new call, although it is possible for the subscriber A' to connect with the trunk to answer the call initiated by the subscriber A, as will be explained presently.

After the intercommunicating lamp 24 lights up, subscriber A will operate the combined ring and transfer key CK to the left 75 in accordance with the code of subscriber A'. After having signalled subscriber A', subscriber A will hold the key CK in the left hand operated position. When the key CK is moved to the left hand operated position the original energizing circuit of relays 42 and 100 is opened at the normally closed springs controlled by spring 47. Relay 100 deenergizes but relay 42 is held energized over the following circuit: from grounded conductor 17 as previously traced, winding of relay 42, armature 40, working contact of spring 47 and said spring, resistance 39, conductor 38, conductor 19, to battery at common conductor 16. Relay 100, upon deenergizing, at armature 101 removes ground from common conductor 6, thereby extinguishing the lamps 24, 24', etc. By the operation of spring 49 into engagement with its working contact (responsive to the operation of key CK to the left) a circuit is closed from ground through the winding of relay 103, conductor 15, conductor 29, spring 49, resting contact of springs 37 and 33, conductor 21, lamp 24, to battery at common conductor 16. 100 Relay 103 energizes over the above-traced circuit but due to the high resistance of relay 103 the lamps 24, 24', etc., do not receive sufficient energy to light brightly. However, relay 103 at armature 109 short circuits itself 105 and connects direct ground to common conductor 15. The effect of this short circuit causes relay 103 to operate in a buzzer like manner and also causes the lamps 24, 24', etc., to flash in response to the intermittent operation of relay 103. By the operation of spring 48 into engagement with its working contact 110 a circuit may be traced for operating all of the buzzers 43 and 43', etc., responsive to each closure of such springs. This circuit may be traced as follows: from grounded conductor 17, conductor 28, spring 44, spring 48, buzzer 43, and conductor 19 to battery at conductor 16, and by way of conductor 20 and common conductor 18 through all of the buzzers, such as 43', etc., to battery at common conductor 16. All the buzzers, therefore, operate in accordance with the operation of the key CK. From the foregoing, it will be seen that spring 47 maintains relay 42 energized, opens 115 the before mentioned shunt circuit to permit other subscribers to come in on this trunk line, and controls, in combination with spring 49, the flashing signal of the intercommunicating lamps, while the spring 48 controls the 120 125

operation of the buzzers of all the local subscribers.

After recognizing his code signal and observing the flashing of lamp 24', subscriber A' will answer on the trunk corresponding to this lamp. In case the trunk key TK' is not already in correct position, that is, the position which corresponds to the flashing lamp, subscriber A' will move the key to such a position that the key will be opposite the flashing lamp. In this instance, since the flashing lamp is 24', or the middle lamp in the vertical row, the key TK' will have to be in its middle or normal position, that position being the position shown in the drawings. Subscriber A' now removes his receiver and responsive thereto a circuit for energizing line relay 42' may be traced as follows: from ground by way of common conductor 17, cradle springs 44', winding of relay 42', resistance 41', normally closed springs controlled by spring 47', springs 51', spring 34' and its resting contact, spring 30' and its resting contact, common conductor 5 and through the winding of relay 100 to battery. Relay 42' energizes in series with relay 100 over this circuit because the previously mentioned low resistance shunt is at this time open at springs 47 at substation A. Relay 42', upon energizing, at armature 40' short circuits resistance 41' and at armatures 45' and 46' connects the telephone set of subscriber A' to the talking conductors of the intercommunicating trunk by way of the heavy talking conductors and springs 35' and 36', and 31' and 32' of the trunk key TK'. The operation of relay 100 at this time again connects ground to common conductor 6, whereupon the lamps 24, 24', etc., burn steadily without flashing. When subscriber A observes that the lamp 24 has stopped flashing and is now burning steadily he will release the key CK and permit it to return to normal position. The circuit for relay 42 is again completed in series with relay 100 when the normally closed springs controlled by spring 47 close responsive to the key CK returning to its normal position. Relays 42 and 42' are maintained energized in parallel and in series with relay 100. Subscriber A and subscriber A' are now connected together and may talk over the heavy talking conductors, the battery being furnished over conductors 3 and 4. After conversation, subscribers A and A' will replace their receivers thereby opening the circuits of relays 42 and 42' at cradle springs 44 and 44', respectively. The circuit of relay 100 is also opened and accordingly said relay deenergizes and at armature 101 removes ground from conductor 6, thereby extinguishing the lamps 24, 24', etc.

Having described the operation which takes place when a local subscriber desires to call another subscriber over the intercommunicating trunk, a description will now be

given of the operation which takes place when a local subscriber desires to complete a connection with a main exchange subscriber. For this purpose we will assume that subscriber A desires to complete a connection with a main exchange subscriber. After observing that lamp 23, for example, is dark, subscriber A will operate the trunk key TK to the left in order to seize this trunk line. The operation of the key TK to the left does not perform any function at this time, but responsive to the removal of the receiver from the cradle set relay 42 is energized from grounded common conductor 17 by way of conductor 28, cradle springs 44, winding of relay 42, resistance 41, normally closed springs controlled by spring 47, springs 51, spring 34 and its resting contact, spring 30 and its working contact, conductor 13, and through the lower winding of ring-up relay 104 to battery. Relays 42 and 104 energize over the above-traced circuit, relay 42 performing the same functions as previously described and relay 104 at armature 110 grounding conductor 14 to light the lamps 23, 23', etc. By the operation of armatures 45 and 46 by relay 42, the substation set A is bridged across the trunk line, thereby energizing line relay 117 of the rotary line switch RS in the main exchange. Relay 117, upon energizing, at armature 121 grounds release trunk conductor 128 to make this trunk line busy to the connector switches having access thereto, and also prepares a circuit for the switching relay 116 in series with stepping magnet 118. The operation of the rotary line switch RS now depends upon whether the wipers 125 to 127, inclusive, are resting upon an idle or busy trunk. Assuming that the wipers are resting on a busy trunk, test wiper 126 engages a grounded busy contact. The ground prevents the operation of relay 116, but energizes the stepping magnet 118, and such magnet interrupts its own circuit and steps the wipers of the rotary line switch to the next trunk. If this trunk is busy the magnet operates again and the wipers continue to rotate until the test wiper 126 engages an idle contact, whereupon switching relay 116 energizes, since it is no longer short circuited. Relay 116, upon energizing, at armature 120 opens the circuit of the stepping magnet 118 at its resting contact and at its working contact connects ground by way or armature 121 to test wiper 126 for temporarily rendering this trunk busy. At armatures 119 and 124 the talking conductors are cut through to the wipers 125 and 127, whereupon the line and release relays in the selector S operate in the well known manner and the release relay transmits ground back over the release trunk to maintain relay 116 energized and this trunk line busy. When the talking conductors 11 and 12 are

cut through to the selector S dial tone through the lower winding of the line relay of the selector S is transmitted to the subscriber A over the heavy talking conductors in the well known manner.

Subscriber A, upon hearing the dial tone, will operate his calling device CD in accordance with the directory number of the called main exchange subscriber. The operation from now on is purely automatic operation and being well known need not be explained further. Both subscriber A and the main exchange subscriber are furnished with talking battery from the connector switch in the main exchange. After conversation subscriber A replaces the monophone on the cradle, thereby separating the springs 55 and 44, whereupon the switches in the main exchange and line relay 42 release. It is not necessary at this time for the subscriber to restore the key TK to its normal position because the key in operated position does not have any effect until the monophone is removed from its cradle.

Having described how outgoing calls from the local exchange are completed to main exchange subscribers, a description will now be given of the operation which takes place when a main exchange subscriber calls a local subscriber. For this purpose, it will be assumed that a main exchange subscriber has operated the connector C, Fig. 2, into engagement with the bank contacts in which the trunk conductors 11 and 12 terminate. When this takes place, if the trunk line is idle, relay 132 energizes in series with switching relay 116 in the well known manner. Due to the mechanical interlocking arrangement of the rotary line switch the switching relay 116 operates its armatures to disconnect the trunk conductors from the winding of line relay 17 at armature 119 and ground at armature 124, but does not connect up the switch wipers. Responsive to the operation of the switching relay 132 a circuit may be traced for operating the ring-up relay 104 as follows: from interrupted generator INT. GEN, at the contacts of armature 134, armature 136, wiper 139, bank contact 142, conductor 12, upper winding of relay 104, condenser C, conductor 11, bank contact 140, wiper 137, armature 135, armature 133 and its resting contact, and through the upper winding of ring-cut-off relay 131 to battery. Relay 104 is intermittently operated responsive to the intermittent application of generator, and said relay at armature 110 connects ground to common conductor 14 for intermittently operating the trunk lamps 23, 23', etc. Any local subscriber, upon observing the flashing of a trunk lamp, such as 23, may answer the call by first operating his trunk key such as TK to the position opposite the flashing lamp. After the operation of the trunk key

to this position the subscriber will then remove the monophone from its cradle.

Let it be assumed that subscriber A answers the call in the manner just described. Responsive to the removal of the monophone from its cradle stand at substantion A, line relay 42 is energized in series with the lower winding of relay 104 as previously described. Relay 104 is maintained energized over this circuit and therefore the lamps 23, 23', etc., burn steadily, which is an indication that the call has been answered and the trunk line is busy. By the operation of armatures 45 and 46, relay 42 closes a direct current bridge across the talking conductors 11 and 12, thereby causing the operation of the ring-cut-off relay 131 in the connector C. Ring-cut-off relay 131 energizes and locks itself and at armatures 133 and 134 completes the talking circuit and the circuit for the back-bridge relay 130 for feeding battery to subscriber A. The main exchange subscriber and subscriber A converse over the heavy talking conductors as desired.

It will be assumed now that the main exchange subscriber wishes to have the call transferred to another local subscriber. The main exchange subscriber informs subscriber A that a connection with subscriber A', for example, is desired. Thereupon subscriber A will operate the combined ring and transfer key CK to the right in accordance with the code of subscriber A' and then maintain the key CK in its right hand operated position until the lamp 23 quits flashing and burns steadily. It will be noted that springs 52 and 53 are connected in parallel with springs 48 and 49 and therefore perform the same function as such springs; that is, springs 53 controls the flashing of the lamps and spring 52 controls the operation of the buzzers. The operation of spring 50 into engagement with its working contact bridges impedance 54 across the talking conductors 11 and 12 in order to maintain a direct current bridge across such conductors when relay 42 deenergizes and opens the direct current bridge including the substation equipment at armatures 45 and 46. At spring 51 and its resting contact the circuit of relay 42 is opened, whereupon such relay deenergizes. The circuit extending through the lower winding of relay 104 is also opened at springs 51 and accordingly relay 104 deenergizes and at armature 110 removes the ground from conductor 14. This removal of ground from conductor 14 and the operation of relay 103, as previously described, causes the lamps 23, 23', etc., to flash. The circuit for energizing relay 103 is extended at this time by way of springs 53 instead of springs 49. The circuit for the buzzer includes the common grounded conductor 17, cradle springs 44, springs 52, and common conductor 16 to battery.

Subscriber A', upon recognizing his code

ring and observing which lamp is flashing, in this case lamp 23', will operate the trunk key TK' to the left opposite such lamp, and then remove his monophone from the cradle. Responsive to the removal of the monophone from its cradle set, relays 104 and 42' energize over the following circuit: from ground by way of common conductor 17, cradle springs 44', winding of relay 42', resistance 41', normally closed springs controlled by spring 47', spring 51', spring 34' and its resting contact, spring 30' and its working contact, conductor 13, and through the lower winding of relay 104 to battery. The reoperation of relay 104 causes the lamps 23, 23', etc., to burn steadily, which indicates to subscriber A that the subscriber A' has answered and is connected with the interoffice trunk line. Subscriber A releases the key CK and replaces his monophone on the cradle set. Subscriber A cannot again come in on this trunk because relay 42 will not energize in series with resistance 41 due to the low resistance shunt closed by armature 40' of relay 42'. The main exchange subscriber and subscriber A' may converse over the heavy talking conductors as desired. In case during such conversation the main exchange subscriber desires to talk to both subscribers A and A' at the same time, the main exchange subscriber will inform subscriber A' of such intention and subscriber A' will operate the key CK' to the left in accordance with the code of subscriber A. The operation of key CK' to the left in accordance with the code causes the relay 104 to deenergize, causes relay 42' to be held in series with resistance 39' over common conductor 16, causes the operation of the buzzers in accordance with the code of subscriber A and causes the flashing of lamps 23, 23', etc., in a manner similar to that described for establishing an intercommunicating connection. Subscriber A, upon recognizing his code, and noting the flashing of lamp 23, thereupon operates his trunk key TK to the left and removes his monophone from the cradle. Relay 42 energizes in series with relay 104. At armature 110 relay 104 causes the lamps 23, 23', etc., to burn steadily. Relay 42 is permitted at this time to energize in series with relay 104 because by the operation of the springs 47' the low resistance shunt has been opened at the normally closed springs controlled by springs 47'. Relay 42' is maintained energized in parallel with relay 42 after springs 47' are returned to normal. The subscribers may carry on conversation over the heavy talking conductors. After conversation subscribers A and A' replace their monophones on the cradle set, thereby opening the circuit of relays 42, 42' and 104, whereupon the apparatus is returned to its normal position and the lamps 23, 23', etc., are rendered dark. In case it is considered objectionable to have

the lamps burn steadily when the trunks are busy a simple modification can be readily made by adding a pair of normally open switch hook springs similar to 44' and have the battery conductor 26 extend through these added springs to the lamps. With this arrangement it will be obvious that the lamps will burn only after the receiver is removed. In order to take care of incoming calls with the above modification, a common signal would be provided to indicate an incoming call and on such a call the lamps would not flash until the subscriber removed his receiver.

The invention having been fully described, what is considered new and is desired to have protected by Letters Patent will be pointed out in the appended claims.

What is claimed is:

1. In a telephone system, a plurality of subscribers' stations, an incoming trunk common to said stations, a signal for said trunk at each of said stations, means for intermittently operating all of said signals for indicating an incoming call responsive to the seizure of said trunk, subscriber controlled means at each of said stations for answering said call and completing connection between the trunk and the answering station, and means responsive to a subscriber answering for excluding all other subscribers from completing connection with said trunk.

2. In a telephone system, a plurality of subscribers' stations, an incoming trunk common to said stations, a signal for said trunk at each of said stations, means for intermittently operating all of said signals for indicating an incoming call responsive to the seizure of said trunk, subscriber controlled means at each of said stations for answering said call and completing connection between the trunk and the answering station, means responsive to a subscriber answering for excluding all other subscribers from completing connection with said trunk, and subscriber controlled means for transferring such call to another subscriber's station.

3. In a telephone system, a plurality of subscribers' stations, a trunk common to said stations, a signal for said trunk at each of said subscribers' stations, a key at each of said subscribers' stations for preparing a connection between the station and said trunk, means responsive to the removal of the receiver by a calling subscriber for closing the prepared connection, means operative responsive thereto for operating all of said signals at said subscribers' stations, means for preventing another subscriber from seizing said trunk, and manually operated means at said calling station for code signalling a desired subscriber, for intermittently operating all said signals, and for permitting the called subscriber upon answering to complete connection to said trunk.

4. In a telephone system, a plurality of subscribers' stations, a plurality of trunks common to said stations, a signal for each of said trunks at each of said subscribers' stations, the unoperated condition of said signals indicating idle trunks, means for operating a signal to indicate a call on a trunk, and means for operating such signal steadily when the call is answered to indicate that the trunk is 10 busy.
5. In a telephone system, the combination of a plurality of subscribers' stations, of a plurality of trunks common to said stations, a signal for each of said trunks at each of said 15 subscribers' stations for indicating the idle or busy condition of said trunks, and means for flashing all the signals associated with any particular trunk to indicate an incoming call.
6. In an intercommunicating telephone system, a plurality of subscribers' stations, a plurality of trunks common to said stations, means controlled by a calling subscriber for audibly signalling a desired called subscriber, 20 and means for visually indicating to the called subscriber which trunk to answer the call on.
7. In an intercommunicating telephone system, a plurality of subscribers' stations, a plurality of trunks common to said stations, means controlled by a calling subscriber for audibly signalling a desired called subscriber, 25 means for visually indicating to the called subscriber which trunk to answer the call on, and means controlled by the response of the called subscriber for visually indicating to the calling subscriber that the called subscriber has answered.
8. In combination with a plurality of subscribers' stations, of a plurality of trunks common to said stations, a single key having a different position corresponding to each of said common trunks at each subscriber's substation, and means at each subscriber's station 40 responsive to the removal of the receiver thereat for connecting such subscriber's station to the trunk corresponding to the operated position of the key at such station.
9. In combination with a plurality of subscribers' stations, of a plurality of trunks common to said stations, a single key having a different position corresponding to each of said common trunks at each subscriber's substation, means at each subscriber's station 45 responsive to the removal of the receiver thereat for connecting such subscriber's station to the trunk corresponding to the operated position of the key at such station, and means responsive to such connection for preventing a second subscriber from completing connection with the trunk in use.
10. In combination with a plurality of subscribers' stations, of a plurality of trunks common to said stations, a single key having 50 a different position corresponding to each of said trunks at each subscriber's station, the unoperated condition of said signals indicating idle trunks, means at each subscriber's station responsive to the removal of the receiver thereat for connecting such subscriber's station to the trunk corresponding to the operated position of the key at such station, and means responsive to such connection for preventing a second subscriber from completing connection with the trunk in use.
11. In a telephone system wherein a plurality of subscribers' stations have access to a common trunk, a connecting relay individual to each of said subscribers' stations, means at a calling station for energizing one of said relays to seize said trunk, and means controlled by said relay for preparing a low resistance shunt circuit for the remaining relays to make said trunk non-seizable by another station. 80
12. In a telephone system wherein a plurality of subscribers' stations have access to a common trunk, a connecting relay individual to each of said subscribers' stations, means at a calling station for energizing one of said relays to seize said trunk, means controlled by said relay for preparing a low resistance shunt circuit for the remaining relays to make said trunk non-seizable by another station, and subscriber controlled means at the calling station for opening the shunt circuit to permit another relay to energize to cause another subscriber to be connected to said trunk. 85
13. In an intercommunicating system, a plurality of stations, a selecting key at each station, each key having a normal position and two operated positions, a local trunk associated with the normal position of each key, and two main exchange trunks associated with the two operated positions of each key, respectively. 90
14. In an intercommunicating system, a plurality of stations each including a telephone and a selecting key, a plurality of trunks selectable by said keys, means responsive to the removal of the receiver at any calling telephone for connecting the same to the trunk selected by the associated key, means for preventing the connection of any other telephone to said trunk, a signalling key at the calling station for signalling a called station, and means dependent on the continued actuation of said signalling key for rendering said preventing means temporarily inoperative, so that the called telephone can be connected to the trunk. 115
15. In a telephone system, a plurality of subscribers' stations, an incoming trunk common to said stations, a signal at each of said stations operated responsive to the seizure of said trunk at the distant end, means at each 120

of said stations for answering said call, and means at the answering station for transferring the call to any other of said stations.

16. In a telephone system, a plurality of subscribers' stations, a plurality of incoming trunks common to said stations, a plurality of signals at each station, one for each trunk, means responsive to the seizure of one of said trunks at the distant end for operating the signal associated with the seized trunk at each station, and subscriber controlled means at each station for answering the call and for transferring the call to any other of said stations.

15 17. In a telephone system, a plurality of stations, a trunk common to said stations, means at a calling station for connecting the station to the trunk, means for preventing the connection of any other station to said 20 trunk, a key for signalling a called station, and means dependent upon the continued operation of said key for rendering said preventing means inoperative to allow said called station to be connected to said trunk.

25 18. In a telephone system, a plurality of subscribers' stations, a plurality of incoming trunks common to said stations, signals at each of said stations, means common to all of said stations for operating said signals to 30 notify the subscribers at all of said stations of an incoming call on one of said trunks and of the particular trunk on which the call is waiting, and means at each station for answering said call.

35 19. In a telephone system, a plurality of subscribers' stations, a plurality of incoming trunks common to said stations, signals at each station for notifying the subscriber thereat of an incoming call on one of said 40 trunks and of the particular trunk on which the call is waiting, means at each station for answering said call, and means responsive to the answering of the call at any station for operating the signals in a distinctive manner 45 to notify the subscribers at the remainder of the stations that the call has been answered.

20. In a telephone system, a plurality of subscribers' stations, a plurality of incoming trunks common to said stations, means at 50 each station for notifying the subscriber thereat of an incoming call on one of said trunks and of the particular trunk on which the call is waiting, means at each station for answering said call, and means for preventing the connection of any other station to said 55 trunk.

21. In an intercommunicating system, a plurality of stations, a three position key at each station, and three trunks common to said stations, the first trunk being connected to the contacts of one position of each key and the other two trunks being connected to the contacts of the other two positions of each key, respectively.

65 22. In combination with a telephone sys-

tem wherein all switching necessary to the establishment of talking connections is accomplished at the substations, a trunk line extending from a distant exchange having branch connections terminating in the 70 switching apparatuses of the stations of such system, apparatus at one of the stations of said system for enabling an incoming call to be answered, a plurality of other stations, and means at said one station for transferring the connection to any other desired one of said stations of the system.

In witness whereof, I hereunto subscribe my name this 14th day of February, A. D. 1929.

CLARENCE A. ANDERSON.
